MACHINE FOR DRAWING SHAPES IN SHEET METAL

Richard A. Paulton, Cozzadale, Ohio, assignor to The Cincinnati Milling Machine Co., Cincinnati, Ohio, a corporation of Ohio

Application April 3, 1958, Serial No. 50,318

Term of patent 14 years

(Cl. D54—14)

Fig. 1 is a front elevational view of a machine for drawing shapes in sheet metal, embodying my new design; Fig. 2 is a side elevational view thereof.

The rear and side portions not shown are substantially plain, and the tops of both the cylindrical and rectangular elements, not shown, are substantially plain and flat.

The dominant features of the design reside in the portions shown in full lines.

I claim:

The ornamental design for a machine for drawing shapes in sheet metal, as shown and described.
